UNITED STATES PATENT OFFICE

152,508

DESIGN FOR A COAT OR THE LIKE

Robert Trigére, New York, N. Y.

Application September 22, 1948, Serial No. 148,697

Term of patent 3½ years

(Cl. D3—4)

To all whom it may concern:

Be it known that I, Robert Trigére, a citizen of the United States, residing in the city of New York, the county of New York, and State of New York, have invented a new, original, and ornamental Design for a Coat or the like, of which the following is a specification, reference being had to the accompanying drawing, forming part thereof.

Fig. 1 is a front view of a coat or the like, showing my new design.

Fig. 2 is the rear view of the coat shown in Fig. 1.

Fig. 3 is a fragmentary view of the coat shown in Fig. 1 with the cape member removed.

Fig. 4 is the fragmentary rear view of the coat shown in Fig. 3, and

Fig. 5 is a fragmentary side view of the coat, illustrating it in unbuttoned position with the side fullness in loosened position.

I claim:

The ornamental design for a coat or the like, substantially as shown and described.

ROBERT TRIGÉRE.
